Primary Examiner — Clare E Heflin(57) **CLAIM**

The ornamental design for a solar torch light, as shown and described.

DESCRIPTION

FIG. 1 is a front elevational view of a solar torch light showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof.

The symbolic break in the drawings indicates the appearance of any portion of the article between the break lines forms no part of the claimed design.

The broken lines in the drawings illustrate portions of the solar torch light which form no part of the claimed design.
